UNITED STATES PATENT OFFICE.

JOSEPH S. REYNOLDS, OF LOS ANGELES, CALIFORNIA.

SCRAPER.

Application filed June 2, 1924. Serial No. 717,273.

To all whom it may concern:

Be it known that I, JOSEPH S. REYNOLDS, a citizen of the United States, residing at Los Angeles, in the county of Los Angeles, State of California, have invented a new and useful Scraper, of which the following is a specification.

This invention relates to scrapers and relates particularly to a scoop control mechanism therefor.

A type of scraper to which my invention is especially applicable consists essentially of a scoop member having a means pivoted thereto by which it may be drawn. The scoop is drawn over the ground to be levelled by a suitable tractive means so that it scrapes the surface thereof and the removed earth accumulates in the scoop. When the scoop is full, the cutting edge thereof is removed from engagement with the ground by the actuation of a scoop control mechanism. When it is desired to dump the load of dirt, the control mechanism is further actuated in a manner such as will allow the scoop to be rotated into dumping position.

The general type of scoop mechanism with which the inventor is familiar is so constructed and arranged as to be engageably associated with the scoop at two places; namely, near each end thereof. It is intended that when the mechanism is actuated for dumping, the engagements thereof with the scoop will be simultaneously released. It is found, however, that in actual practice they do not always release at the same time. Releasing of one engager prior to the releasing of the other allows one end of the scoop to partially rotate. This incurs a considerable strain in the scoop and its associated parts, distorting the different parts and making the life of the scraper much shorter than it would be if this did not occur.

It is an object of this invention to provide a control means which will overcome the above expressed disadvantage. I do this by providing only one engagement between the control mechanism and the scoop.

My invention consists essentially of stop members which are secured to or associated with the scoop and which rest in substantially the same circumferential plane. The stop members are arranged to be engaged by an engager member which may be situ-

ated on a releasing arm. When it is desired to dump a load of dirt previously accumulated, the releasing arm is actuated by a suitable actuating member in such a manner as to release the engagement between one of the stop members and the engager. This allows the scoop to rotate and the earth to be dumped therefrom.

It is also an object of this invention to provide a means for adjusting the various positions which the scoop is arranged to assume. I provide the above mentioned adjustability by adjustably associating the stop members with the scoop.

It is a further object of my invention to provide a means for regulating the depth of cut, which the scoop will take. I accomplish this by mounting the releasing member on a swingable lever, which lever may be swung from the driver's seat of the tractive vehicle pulling the scraper. A swinging of the release arm will vary the position of the engager and thereby adjust the position of the stop.

It is also an object of the invention to provide a control mechanism which may very facilely be actuated from the driver's seat of the traction vehicle.

Further objects of the invention and the specific advantages thereof will be made evident hereinafter.

Referring to the drawings which are for illustrative purposes only,

Fig. 1 is a side view of a scraper embodying a control mechanism which presents the various features of my invention, the scoop thereof being shown in cutting position in this view.

Fig. 2 is a plan view of Fig. 1.

Fig. 3 is a section taken on a plane as indicated by the line 3-3 of Fig. 2, this view clearly depicting the construction of my control mechanism.

Fig. 4 is a fragmentary side view showing the relative position of the different parts when the scoop is in dumping and levelling position.

Fig. 5 is a view taken as indicated by the line 5-5 of Fig. 1.

Fig. 6 is a perspective view showing the particular type of stop members which I employ.

Fig. 7 is a view showing a reversible type of stop member.

As shown in the drawings, numeral 11

represents a scoop having a bottom 12 which is directed upwardly at the rear to form a back 13. Side members 14 are secured to the bottom 12 and the back 13 in any suitable manner, such as by angle irons. An angle iron 15 is riveted to the upper edge of the back 13 in order to prevent any distortion in the scraper. Runner bars 17 which may be in the form of angle irons, as shown, are secured to the side 14 by suitable rivets 18, the runner bar 17 having the shape substantially as shown in Fig. 1. Runner shoes 19 are secured to each of the runner bars 17 in any suitable manner, such as by rivets 20. Stub shaft blocks 22 are secured, as shown, to the sides 14 by rivets 23, the blocks 22 presenting stub shafts 24 on which side bars 25 are rotatably disposed. The side bars 25 extend forwardly from the stub shaft 24 and are converged at the extreme forward end thereof, as clearly shown in Fig. 2, in a manner to meet the central bar 26.

The side bars 25 and the central bar 26 are secured together in any suitable manner and have a link 27 secured thereto, which, as shown in Fig. 1, may extend into a clevice 28 provided on a tractor vehicle 29. A pin 30 is extended through the legs of the clevice to retain the link 27 therein.

The central bar 26 at its rearward end abuts against a cross bar 32. This cross bar 32 is bent rearwardly at each end thereof and is secured to the side bars by suitable rivets 33. Angle plates 34 are provided for the purpose of rigidly securing the central bar 26 to the cross bar 32, there being rivets 36 to provide this securing.

The scraper arrangement which I have just described is old in the art and in no way constitutes a part of this invention. My invention comprises solely a control mechanism and may optionally be employed on a number of types of scrapers.

My control mechanism comprises a stop supporting member or bar 44 secured to the bottom 12 of the scoop 11 by means of the angle irons 45, which have rivets 46 passing therethrough. The bar 44 is preferably bent into a shape similar to the runner bars 17. Stops 47 are secured to the bar 44, as clearly shown in Fig. 6. The stops 47 are preferably formed from a plate member which is bent into a U-shape so as to form a pair of parallel extending legs 48 which, when the stops are in place, extend to either side of the bar 44. Bolts 49 are provided for securing the stops 47 rigidly in place. The bar 44 is provided with a number of holes 51 adjacent to each stop 47 so as to provide an adjustability of the stops 47, these stops being moved in either direction as desired.

Pivot brackets 53 are secured, as clearly shown in Fig. 2, to each side of the angle plates 34 and extend downwardly as shown.

A pivot pin 54 extends between the brackets 53 and an adjusting member or lever 55 is pivoted thereon. As shown in Fig. 2, the lever 55 has a member 56 secured thereto by rivets 57 at the rearward end thereof in a manner to provide a pair of parallel legs 59, these legs extending to each side of the brackets 53. The adjusting member 55 is curved upwardly at 60 and extends forwardly so that the extreme forward end 61 thereof is in a position adjacent to the driver's seat 62 of the tractor 29, the lever being offset as shown in Fig. 2 so as to extend to one side thereof.

A toothed bar 64 is secured to the central bar 26, having teeth 65 formed on the forward edge thereof. The lever 55 has an engaging pawl 67 arranged thereon, which is adapted to engage between the teeth 65 of the bar 64. Extending from the pawl 67 is a wire or connecting member 68, which at its forward end attaches to a hand lever 70, this hand lever being secured at the extreme forward end 61 of the lever 55. By depressing the lever 70 movement is imparted to the wire 68 in a manner to remove the pawl 67 from engagement between the teeth 65 so that the lever 55 may be swung into any desired position, a spring being provided to return the pawl into engagement with the teeth 65 when the hand lever 70 is released.

To the rearward side of the pivot 54 and at the extreme rearward end of the legs 59, a releasing member or arm 73 is pivoted, as shown, by a suitable pin or rivet 74. The arm 73 is preferably formed from a flat steel bar which is bent into U-shape so as to provide a pair of parallel extending legs or arms 76, as clearly shown in Fig. 5. An engager or roller 78 is secured by means of a pin 79 between the legs 76 of the releasing member 73. As shown in Fig. 3, the engager 78 is arranged to engage an adjacent stop 47. A means for holding the engager 78 normally in engaging position, or, in other words, the arm 73 in its rearward position, is shown in the form of a rod 80 which has its forward end bent at 81 so as to extend through the central bar 26 for securing it at one end. The other end of the rod 80 extends through a plate 83 which is secured to the member 73. A collar 84 is placed on the rod 80 and a spring 84^a is compressed between the collar 84 and the plate 83 in a manner to yieldingly force the lever 73 into its rearward position. A nut 85 is screwed onto the rearward end of the rod 80 to adjust the rearward position of the arm 73. A ring 86 is secured to the upper end of the arm 73 and has secured thereto an actuating member in the form of a rope 87 which extends forwardly and may be tied, as shown in Fig. 1 at a suitable place 89 to the tractor 29.

The actuation of the mechanism just described during the usual operation of the scraper is as follows:

In Fig. 1 the scoop is shown in scraping position, that is, the forward cutting edge 92 of the bottom 12 of the scoop is positioned so as to be in engagement with the ground. The scraper being pulled forwardly over the ground by the tractor 29 removes the upper surface of the ground, filling the scoop 11. When the scoop 11 is filled, it is moved from the position shown by the full lines in Fig. 1 and Fig. 3 into carrying position as shown by the dotted lines 94 of Fig. 3. This is accomplished by the operator swinging the lever 55 from the position shown in full lines in Fig. 3 into the dotted lines 96, it being of course necessary to release the pawl 67 as described before. It will be seen that the swing of the lever 55 swings the arm 73 upwardly, which moves the engager 78 upwardly, and the engager being contacted by a stop 47 will in turn raise the stop therewith. This action results in a tilting of the scoop 11 in such a manner that the cutting edge 92 is removed from engagement with the ground, the scoop then riding on the rearward portion 98.

When it is desired to dump the dirt, the mechanism is actuated so as to allow the scoop to rotate in the direction indicated by the arrow 100 of Fig. 3. This is accomplished by the operator pulling forwardly on the rope 87, which swings the arm 73 forwardly, thereby removing the engager 78 from engagement with the adjacent stop 47 in a manner to allow the scoop to rotate. If the operator desires to dump the earth in a pile, such as for the purpose of forming irrigation ditches or the like, he holds the engager out of engaging position until the second stop 47, indicated at 101, has passed the engager 78. If the operator desires to spread the earth over the surface of the ground, he may do this by merely holding the arm 73 forward until the engaged stop 47 passes the engager 78. He then releases the arm 73 so that the engager will engage the second stop 101, which will retain the scoop in the position shown in Fig. 4. From Fig. 4 it will be seen that the earth being dumped will be spread over the surface of the ground by the edge 92 of the scoop. In order to prevent any excess movement in the scoop 11 when in scraping position, or carrying position, due to engagement of the scoop with obstructions such as rocks, I provide an auxiliary stop 103 which is located adjacent to a stop 47, which stop 103 retains the scoop in scraping or carrying position. It will be seen that the engager, when resting between the stops 47 and 103, will prevent any up and down motion in the scoop. In order to assure the engager engaging the stop 47, I have made the auxili-

ary stop 103 slightly shorter, as clearly shown in Fig. 4, this auxiliary stop 103 merely being long enough to engage with the engager 78 when it is in its extreme rearward position.

To adjust the amount or depth of cut that the scraper will take, the operator merely lowers or raises the engager by moving the adjusting lever 55 up or down to suit. It will be seen that it is possible to move the lever 55 a short distance in either direction by engaging between other teeth on the bar 64.

Further adjustments may be had by changing the position of the stop 47 on the mounting bar 44 by placing the bolts 49 through different holes 51 in the bar. Likewise the levelling position of the scraper may also be adjusted by moving the other stop 47 in a similar manner.

From Fig. 4 it will be seen that the lower stop 47 will engage the ground and may be subjected to attrition. In the event that this wear should be considerable, the stop 47 would wear down to the extent that it would fail to perform its duty, and replacement would be necessary. In Fig. 7 is shown a reversible stop 105 which has holes 106 provided therein, through which bolts 107 may extend. The stop 105 is so proportioned that when the portion 109 wears considerably, it may be reversed and the life thereof doubled.

From the foregoing description it will readily be seen that a scraper equipped with a control mechanism of my invention may be used and will accomplish the same work as any of those scrapers employing intricate mechanism. My invention provides a control which is very simple in construction, containing few parts, and which is very simple to operate.

I claim as my invention:

1. In a scraper of the character described, the combination of: a draft device; a scoop pivotally mounted on said draft device; a stop supporting member secured to said scoop substantially midway between the ends thereof; a stop secured to said member; and means mounted on said draft device for holding or releasing said stop so as to permit the scoop to be held in scraping position, or released to dumping position as may be desired.

2. In a scraper of the character described, the combination of: a draft device; a scoop pivotally mounted on said draft device; a stop supporting member secured to said scoop substantially midway between the ends thereof; a stop secured to said member; means for adjusting the position of said stop on said stop supporting member; and means mounted on said draft device for holding or releasing said stop so as to permit the scoop to be held in scraping position, or

released to dumping position as may be desired.

3. In a scraper of the character disclosed, the combination of: a draft device; a scoop 5 pivotally mounted on said draft device; a stop supporting member secured to said scoop substantially midway between the ends thereof; a stop secured to said member; means mounted on said draft device for 10 holding or releasing said stop so as to permit the scoop to be held in scraping position, or released to dumping position as may be desired; and a second stop for holding said scoop in said dumping position.
- 15 4. In a scraper of the character described, the combination of: a draft device; a scoop pivotally mounted on said draft device; a stop supporting member secured to and between the front and back of said scoop 20 substantially midway between the ends thereof, said supporting member comprising a substantially arcuate bar; a stop carried by said supporting member; means mounted on said draft device for holding or releasing said stop so as to permit the scoop to be held in scraping position or released to dumping position as may be desired; and means for raising the cutting edge of said scoop relative to the frame of said draft device.

or releasing said stop so as to permit the scoop to be held in scraping position or released to dumping position as may be desired.

5. In a scraper of the character described, the combination of: a draft device; a scoop 30 pivotally mounted on said draft device; a stop supporting member secured to and between the front and back of said scoop substantially midway between the ends thereof, said scoop supporting member comprising a 35 substantially arcuate bar; a stop carried by said supporting member; means mounted on said draft device for holding or releasing said stop so as to permit the scoop to be held in scraping position or released to dumping 40 position as may be desired; and means for raising the cutting edge of said scoop relative to the frame of said draft device.

In testimony whereof, I have hereunto set my hand at Los Angeles, California, this 45 24th day of May, 1924.

JOSEPH S. REYNOLDS.
